UNITED STATES PATENT OFFICE.

MICHAEL MOLITOR, OF CALVARY, WISCONSIN.

GRAIN-BINDER.

No. 851,825.

Specification of Letters Patent.

Patented April 30, 1907.

Application filed October 22, 1906. Serial No. 339,924.

To all whom it may concern:

Be it known that I, MICHAEL MOLITOR, a citizen of the United States, and a resident of Calvary, in the county of Fond du Lac and State of Wisconsin, have invented certain new and useful Improvements in Grain-Binders; and I do hereby declare that the following is a full, clear, and exact description thereof.

The object of my invention is to provide means for handling moist grain delivered to the binding-mechanism of a harvester, whereby the said grain is prevented from lodging upon the binder-table, and is formed into smaller bundles than would ordinarily be required, in order that said grain may more readily be dried, said invention consisting in certain peculiarities of construction and combination of parts as hereinafter fully set forth with reference to the accompanying drawings and subsequently claimed.

In the drawings: Figure 1 represents a fragmental view of the binder-end of a harvester, with parts broken away and parts in section, to more clearly illustrate my invention, the features of which are embodied in said view, and Fig. 2, is a plan view of a portion of the same, being partly in section, as indicated by line 2—2 in Fig. 1.

Referring by letter to the drawings, A, A', indicate elevator-aprons, the upper rollers B, B', of the elevator-aprons only being shown, which rollers mounted in the elevator-frame C, as usual. The binder-mechanism D and table E are supported at the delivery side of the elevator-frame, provision being made for lateral adjustment of said binder-mechanism and table, for binding long and short grain in the usual manner. Mounted under the platform table, in bearings a, is a squared shaft b, which shaft carries a series of star-wheels c being spaced apart by thimbles d, the outer two of which rest in the bearings a, and serves as the medium upon which said shaft revolves. One end of this shaft extends beyond the table and carries a drive-sprocket e, which is in chain-belt-connection with a similar sprocket f secured to the lower apron roller shaft, through which motion is imparted to the several star-wheels, the latter being rotated through slots g in the binder-table, and serve to catch the lodged grain as it falls from the elevator and imparts a motion thereto to

deliver the same to the binder. The drive-sprocket e is held against lateral movement, when the binder-table is shifted, by means of a yoke h, that is bolted to the frame of the machine, the arms of said yoke being formed with openings through which the shaft b passes as it moves back and forth with the table.

Grain being delivered to the binder in sufficient quantities for a normal sized bundle, cause the trip-arm i thereof to be pushed back at the proper time, this action rocks a locking-lever j, that is fast to the trip-arm shaft k, and thereby releases the clutch l, which start the driving-gears of the binder-mechanism in motion to tie and complete a bundle.

The above described action is common to binders now in use and being automatic, will always trip to form a bundle of the same size, and in practice it frequently happens, when a damp piece of grain is being cut, it is, as stated, desirable to make the bundles smaller. To this end I have arranged an attachment consisting of a manual trip mechanism in connection with that of the binder, in order that said binder may be tripped at any time independent of the automatic mechanism.

The manual trip-mechanism comprises a square rod m, which extends through a supporting-tube n of the binder, having secured at one end a lever o, a nose p of which projects under the locking-lever j, as shown in Fig. 1 of the drawings. The opposite end of the rod m has mounted thereon a crank q, to which is connected a rod r, that extends rearward within reach of the driver, the said rod being guided in a bracket s, secured to the table, and carries a spiral-spring t interposed between the bracket and a collar of the rod for returning the mechanism to its normal position after being actuated to trip.

By the above described arrangement it will be readily seen that a driver may trip the binder so that a bundle of any size can be formed.

While I have shown the binder-attachment and one method of connecting the same, it is obvious that the manner of connecting to the several makes of binders will require slight mechanical variations in the detail, which would not change the essential feature of my invention however, and in

some instances in place of the hand-trip, I may substitute a foot-power for tripping the binder-mechanism.

I claim:

- 5 1. In a grain-binder a rock-shaft having a trip-arm secured thereto, a locking-lever secured to the rock-shaft, and a clutch controlled by the locking-lever, in combination with an attachment comprising a rod, supporting means for the rod, a lever secured to the rod, provided with an engaging-nose projecting under the grain-binder locking-lever, a crank secured to the rod, and an actuating-rod in connection with the crank, whereby 15 the same is manually operated to release said locking-lever.
2. In a grain-binder, a feed-mechanism provided with grain elevator aprons and an inclined grain-delivering table, a grain-dis-20 lodging mechanism comprising brackets se-

cured to the lower side of the table adjacent to the receiving-end thereof, a squared shaft revoluble in the brackets, slots in the table, star-wheels mounted on the shaft and projecting through the slots in said table, spacing-thimbles on the aforesaid shaft between the wheels and brackets, a driving-sprocket mounted upon said squared-shaft, and a yoke secured to the binder-frame arranged to engage the sprocket, whereby said sprocket is held against lateral motion when the position of table and shaft carried thereby is shifted.

In testimony that I claim the foregoing I have hereunto set my hand at Calumet in the county of Fond du Lac, and State of Wisconsin in the presence of two witnesses.

MICHAEL MOLITOR.
